BRASSIERE

John Anthony Tozzi, Little Neck, N. Y., assignor to Ellen Bra Corporation, New York, N. Y.

Application October 30, 1956, Serial No. 43,580

Term of patent 3½ years

(Cl. D20—4)

Fig. 1 is a front elevational view of a brassiere showing my new design, and

Fig. 2 is a rear elevational view thereof.

I claim:

The ornamental design for a brassiere, as shown.
